UNITED STATES PATENT OFFICE

165,640

COMBINATION FOOD AND FOOD CONTAINERS HOLDING TRAY

Francis X. Dyer and Janann E. Dyer, Chicago, Ill.

Application April 19, 1949, Serial No. 2,143

Term of patent 3½ years

(Cl. D44—10)

To all whom it may concern:

Be it known that we, Francis X. Dyer and Janann E. Dyer, both citizens of the United States, and residing in the city of Chicago, in the county of Cook and State of Illinois, have invented a new, original, and ornamental Design for a Combination Food and Food Containers Holding Tray of which the following is the specification, reference being had to the accompanying drawings forming a part thereof.

In the drawing:

Fig. 1 is a side elevational view of a combination food and food containers holding tray showing our new design.

Fig. 2 is a top plan view.

Fig. 3 is a bottom plan view thereof.

We claim:

The ornamental design for a combination food and food containers holding tray, substantially as shown.

FRANCIS X. DYER.
JANANN E. DYER.
